UNITED STATES PATENT OFFICE.

GEORGE B. KELLY, OF JAMAICA PLAIN, MASSACHUSETTS, ASSIGNOR TO THE AEOLIAN COMPANY, A CORPORATION OF CONNECTICUT.

MUSICAL INSTRUMENT.

1,277,944.

Specification of Letters Patent. Patented Sept. 3, 1918.

Application filed May 13, 1915. Serial No. 27,852.

To all whom it may concern:

Be it known that I, GEORGE B. KELLY, a citizen of the United States, residing at Jamaica Plain, in the county of Suffolk and 5 State of Massachusetts, have invented certain new and useful Improvements in Musical Instruments, of which the following is a specification.

My present invention relates to improvements in automatic musical instruments and relates especially to means in such instruments for preventing the music sheets from drifting out of track with the tracker-bar and for preventing plural sheets from getting 10 out of synchronism with each other.

The advantages of my invention will be apparent to those skilled in the art from an understanding of the following description in connection with the drawings which 20 illustrate one of the specific embodiments my invention may take. In them, Figure 1 is a front elevation partly in vertical section of a tracker-box with music rolls and my improvements; Fig. 2 is an enlarged partial 25 view to illustrate details of Fig. 1; Fig. 3 is a section on the line 3—3 in Fig. 2 looking in the direction of the arrows; Fig. 4 is an enlarged section partly in elevation on line 30 4—4 in Fig. 1 looking in the direction of the arrows; Fig. 5 is an enlarged detail view 35 of part of the take-up spool in Fig. 1; and Figs. 6 and 7 are sectional views partly in elevation on the lines 6—6 and 7—7 respectively in Fig. 5 looking in the direction of the arrows.

I will now describe the specific devices of the drawings:—1—1 are the sides of the tracker-box in an automatic piano or organ. 2 is the tracker-bar. 3 and 4 are a pair of 40 companion perforated music-sheets intended to be played in unison. Either one or both sheets in addition to note sounding perforations may be provided with perforations to control the stops in an organ, or the pedals 45 or other expression devices, etc., in a piano or the like.

Each music sheet is further provided with a central line of sprocket holes 5. The music-sheets are attached to independent 50 music spools 3^a and 4^a.

3^b and 4^b are a pair of take-up spools secured to the spindle 6 whose ends are journaled in suitable bearings in the sides of the tracker box, so that said take-up spools 55 turn together when the spindle is driven.

The means for driving the spindle and take-up spools to effect the unwinding and playing of the sheets, may be suitably applied in any well known or preferred manner to one end 6^a of the spindle.

Reverting to the music-roll spools 3^a and 4^a, each has a plain trunnion 7 and a half-round or flatted trunnion 8. The plain trunnions are located at the outside end of the spools when they are together in playing position and are supported in cup like bearings 9 on the ends of slidable rods 10 supported in sleeves in the sides of the music-box and normally given inward tendency by 60 tension springs 11.

The music-rolls are simultaneously driven on the rewind by means as follows acting in common on their flatted ends 8. 14 is a gear-wheel having a hub 14^a with a half-round part 14^b secured fixedly in the hollow 70 of the hub. The gear-wheel 14 is rotatably supported by the ends of its hub projecting into the bearing-sleeves 15 which in turn are stationarily supported in the ends of the metal straps 16 projecting from the back 75 of the tracker box.

Each music roll is inserted in playing position by inserting its plain trunnion 7 in its cup-bearing 9 and pushing it outwardly until the half-round trunnion 8 can be snapped 80 into the end of the gear-wheel hub with its half-round extremity received into the half-round space in the hub not filled by the above described half-round part 14^b. The result is that when the gear wheel 14 is 85 driven it rotates both music-roll spools, it being understood that said gear or sprocket wheel will be driven in any suitable or preferred manner so as to rewind the sheets 90 after playing.

The individual sheets are prevented from drifting laterally and thereby getting out of registration with the ducts in the tracker-bar and are further prevented from getting 95 out of synchronism by means of sprocket 100 teeth or pins 18 on a tube 19 which in turn is provided interiorly with the spiders 20 having hubs 21. 22 is a rod extending through these hubs and on which they rotatably support the tube 19 and the sprocket 105 teeth 18. Of course, stop or shoulder means is provided to prevent the tube 19 from shifting laterally in either direction as it rotates on the rod 22. The two sets of sprocket teeth are positioned at the right 110

distance apart when the device is made so that when they are engaged by the sprocket holes 5 in the music-sheets, said sheets are in proper registering or playing position 5 on the tracker-bar. The rod 22 is itself supported at its ends by the arms 23 pivoted at 24 to the sides of the music box. The result is that the weight of the sprocket tube will bear yieldingly down on the music- 10 sheets between their spools and the tracker-bar as shown in Fig. 4. Also said sprocket tube may be swung upwardly and back out of engagement with the music sheets for example during the rewind. The sides 1 15 are slotted at 1^a so as not to interfere with the lowered or operating position of the sprocket tube.

The front ends of the sheets will have the usual loops for engagement with the hooks 20 25 on the respective halves of the take-up spool. These hooks are fixed to a single rock-shaft 26 which extends through a longitudinally extending hole through the body portion and flanges of both spools, said 25 rock-shaft being bent outwardly between the take-up spools so as to provide an operating handle 26^a. By turning this handle to the right in Fig. 6, it will simultaneously, lift the ends of the hooks 25 to release the 30 loops of the music sheets or vice-versa to permit them to be engaged with the hooks, which thereupon can be swung back into their loop-holding position by turning the said handle 26^a back into the position shown 35 in Fig. 6.

The mode of operation is as follows: The companion music-rolls are inserted as described in playing position. The sprocket tube 19 will then be lifted and the ends 40 of the sheets drawn down under it and then over the tracker to the take-up spool where their loops are engaged with the hooks on said take-up spool. The sprocket tube will then be lowered to bring its teeth into engagement with the sprocket holes in the 45 sheets, care being taken that the sheets are in synchronism when they are engaged with the sprocket teeth. The clutch will then be thrown in to rotate the take-up spool to 50 unwind and play the sheets simultaneously. Neither sheet can now drift out of registry with the tracker-bar due to. Further, both sheets must travel in synchronism because they were started in synchronism and are 55 kept so by the two sets of sprocket teeth on the tube 19. It will be noted that this tube merely turns idly without any driving effect in the sheets, consequently its teeth will not tear them at the sprocket holes. 60 On the rewind the sprocket tube may be raised out of engagement with the sheets.

For the best results, these companion music sheets should be made in accordance with my copending application Serial No. 65 27852 filed May 13, 1915.

Of course some changes and modifications might be made in the above that are nevertheless within the spirit of this inventive disclosure and these I mean to cover by the annexed claims under the doctrine of equivalents. Further certain of the steps or means might be used without the remainder or in connection with equivalent means. 70

What I claim is:—

1. In an automatic musical instrument, a 75 tracker-bar; companion music sheets provided with lines of sprocket holes; means for driving said sheets over the tracker-bar; and idly turning means for keeping them synchronized comprising sprocket teeth engaging the sprocket holes of all the sheets. 80

2. In an automatic musical instrument, a tracker-bar; companion music sheets provided with lines of sprocket holes; means for driving said sheets over the tracker-bar; and 85 idly turning sprocket wheels connected to rotate together and to severally engage the lines of sprocket holes in the respective sheets so as to keep the sheets synchronized. 90

3. In an automatic musical instrument, a 95 tracker-bar; companion music sheets provided with lines of sprocket holes; means for driving said sheets over the tracker-bar; and a single idly rotatable cylinder having a set of sprocket teeth individual to each sheet, so as to simultaneously engage all the lines of sprocket holes in the sheets. 100

4. In an automatic musical instrument, a tracker-bar; companion music sheets provided with lines of sprocket holes; means for 105 driving said sheets over the tracker-bar; idly turning means for keeping them synchronized comprising sprocket teeth engaging the sprocket holes of all the sheets; and means for supporting said idly turning means so as to bear yieldingly against the sheets.

5. In an automatic musical instrument, companion music sheets provided with lines of sprocket holes; means for keeping them 110 synchronized comprising sprocket wheels connected to rotate together and disposed to engage the sprocket holes in all the sheets; and driving means for said sheets which is independent of said synchronizing means. 115

6. In an automatic musical instrument, a tracker-bar; companion music sheets provided with lines of sprocket holes; means for imparting movement in one direction to said sheets; means independent of the driving 120 means for keeping said sheets synchronized comprising sprocket wheels connected to rotate together and disposed to engage the sprocket holes in all the sheets; and means for supporting the synchronizing means so 125 as to permit it to be swung clear of the sheets.

7. In an automatic musical instrument, a tracker-bar, a music sheet provided with a line of perforations, driving means for 130

sheet, and a freely turning wheel having peripheral projections located so as to engage said perforations when the sheet is in playing position on the tracker-bar to prevent lateral drifting of the sheet.

- 5 8. In an automatic musical instrument, a pair of companion music rolls; and means for operatively supporting and driving them in endwise relation to each other, comprising
10 a rotatable driven part located between the adjacent ends of the rolls, adapted to be interlocked with said ends so that the rolls rotate with the driven part, and bearings for the outer ends of said rolls.
15 9. In an automatic musical instrument, a tracker-bar, independent companion music sheets provided with lines of sprocket holes, means for operatively supporting said sheets relative to the tracker-bar and in endwise relation to each other, single take-up spool means for engagement with said sheets to
20 unwind them simultaneously, and idly turn-

ing means for keeping said sheets synchronized comprising sprocket teeth engaging the sprocket-holes of all the sheets.

25

10. In an automatic musical instrument, a tracker-bar; companion music sheets; means for moving said sheets over the tracker-bar; means independent of the last-named means for keeping said sheets synchronized during such movement; and means for supporting said synchronizing means so as to bear yieldingly against the sheets.

30

11. In an automatic musical instrument, a tracker-bar; companion music sheets; means for moving said sheets over the tracker-bar; idly turning means for keeping the sheets synchronized during such movement; and means for supporting said turning means so as to bear yieldingly against the sheets.

35

In testimony whereof I have signed my name to this specification this 11th day of May, 1915.

GEORGE B. KELLY.
